KNIFE SHARPENING MECHANISM FOR
ROTARY SLICING MACHINE KNIVESCornelis Klingens, La Porte, Ind., assignor to
U. S. Slicing Machine Company, Inc., La Porte,
Ind., a corporation of Indiana

Application September 25, 1950, Serial No. 186,647

6 Claims. (Cl. 51—248)

1

The improved knife sharpening mechanism comprising the present invention is applicable to slicing machines of the general type shown and described in a copending application of Cornelis Klingens, the present applicant, Serial No. 186,646, filed September 25, 1950. The mechanism however may, with or without modification, be adapted for use in connection with a large variety of slicing machines of the type having circular rotary knife blades.

It is an object of the present invention to provide a knife sharpening mechanism, all the operative parts of which are enclosed and substantially concealed within a housing which occupies a position adjacent one side of the motor and knife box housings of the slicing machine in an out-of-the-way position, where it is not conspicuous, and adjacent the peripheral edge of the rotary circular knife proper and which, in this out-of-the-way position, is bodily movable from an inoperative position wherein the sharpening wheels associated with the same are out of register with the cutting edge of the knife to an operative position wherein they are in register with the cutting edge of the knife for subsequent manipulation thereof into actual grinding contact with the knife.

A similar and related object of the invention is to provide a knife sharpening mechanism of this character which, while maintaining substantially the same out-of-the-way location relative to the other operative parts of the slicing machine, may be manually and bodily moved from its operative to its inoperative position, and vice versa, and automatically locked in either position against dislodgment upon manual release of the mechanism.

Another object of the invention is to provide a sharpening mechanism of this character having a sharpening wheel and a burring wheel which, when the apparatus as a whole is located in its operative position of register with the edge of the cutting knife for cutting purposes, has the grinding surfaces of the respective wheels properly oriented relative to the surfaces of the cutting knife to be ground so that, by axial movement of the grinding wheels along their respective axes of rotation, these surfaces may be brought into grinding engagement with the edge of the knife in such a manner as to effect the desired sharpening and burring required of them.

Another object of the invention is to provide such a mechanism which, when positioned for sharpening operations, the grinding wheels thereof are maintained in a retracted position under the influence of a common actuating member,

2

together with yieldable means normally urging the grinding members toward the cutting knife so that upon release of the grinding wheels by the actuating member, the yieldable means will serve to impel the grinding members into their respective grinding positions with such yieldable means constituting the sole means for applying grinding pressure to the grinding wheels.

Yet another object of the invention is to provide 10 a grinding apparatus of this character having an actuating member normally serving to maintain the grinding wheels in their retracted positions and capable of being manually actuated to permit the aforesaid yieldable means to move the 15 grinding wheels into grinding position, and also capable of locking at least one of the grinding wheels in an initial grinding position, so that when the action of the yieldable means operating upon the locked grinding wheel has been 20 expended, the yieldable means is ineffective to cause further grinding operation by the locked wheel.

Another object of the invention is to provide 25 such a grinding apparatus in which the common actuating mechanism for both the sharpening and burring wheel normally assumes a retracted position under the influence of a relatively powerful spring which is sufficient to maintain the sharpening wheel and the burring wheel in their 30 respective retracted positions against the action of the yieldable means tending to move them toward their operative position, and which is also movable to an intermediate position wherein the yieldable means operating upon the grinding and burring wheels, respectively, is applied directly to 35 the surfaces of the cutting knife undergoing grinding, and which is still further movable to a final position wherein the sharpening wheel is locked against further movement, so that its grinding effect may terminate and prevent excessive grinding of the cutting knife.

Another object of the invention in an apparatus of this character is to provide a novel type 40 of adjusting means whereby the axis of rotation of the sharpening wheel may be adjusted throughout a slight degree of angularity to attain proper registry of the grinding surface of the grinding wheel with the edge of the cutting knife.

The provision of a knife sharpening mechanism which is relatively simple in its construction, one which is rugged and durable and which, therefore, may withstand rough usage and is unlikely to get out of order, are further desirable features that have been borne in mind in the production and development of the present invention.

In the accompanying two sheets of drawings forming a part of this specification:

Fig. 1 is a transverse sectional view taken substantially centrally and longitudinally through a knife sharpening mechanism constructed in accordance with the principles of the present invention and showing the same applied to the slicing edge of the cutting knife;

Fig. 2 is a top plan view of the completed structure shown in Fig. 1 with a portion of the cover broken away;

Fig. 3 is a sectional view taken substantially along the line 3—3 of Fig. 2;

Fig. 4 is a sectional view taken substantially along the line 4—4 of Fig. 1;

Fig. 5 is a fragmentary perspective view, somewhat diagrammatic in its representation showing certain applications of force being applied to the sharpening and burring instrumentalities of the present invention;

Fig. 6 is a sectional view taken substantially along the line 6—6 of Fig. 2;

Fig. 7 is a sectional view taken substantially along the line 7—7 of Fig. 2;

Fig. 8 is a vertical sectional view taken along the plane of line 8—8 of Fig. 2.

In all of the above described views similar characters of reference are employed to designate similar parts throughout.

Referring now to the drawings in detail, particularly Figs. 1 to 3, inclusive, a portion of a rotary circular knife of the slicing machine is designated at 10. The sharpening mechanism comprises grinding elements in the form of rotary wheels 12 and 14 of emery or other abrasive material, these wheels constituting respectively the primary and secondary elements of a sharpening wheel assembly and a burr removing assembly. The sharpening wheel 12 is adapted to perform the primary grinding operation on the bevelled edge of the rotary circular knife and the burring wheel knife 14 being adapted to remove the burr formed on the opposed edge of the knife during sharpening thereof.

The sharpening mechanism, including the two grinding wheels 12 and 14, involves in its general organization a framework 16 which may be in the form of an integral casting of irregular shape and which includes a sleeve portion 18 slidably mounted upon a post 20 secured in any suitable manner to the framework of the slicing machine and preferably to the knife box casing 21 thereof. A guard or cover 22 of generally cup-shaped design may be secured by means of screws 24 to the framework 16 and is adapted to at least partially enclose the operative grinding instrumentalities of the mechanism. The sharpening mechanism as a whole may be tilted vertically about the axis of the post 20 to enable the burring wheel 14 to clear the upper edge of the slicing machine knife 10 when the sharpening mechanism is moved from its inoperative to its operative position, all in a manner that will be made clear presently.

Referring now to Fig. 3, the sharpening wheel 12 is secured by fastening means 26 to one end of a rotatable spindle 28 and the latter is journaled in a non-rotatable sleeve 30 forming part of a casting designated in its entirety at 32. The casting 32 includes a web portion 34 which extends from the sleeve portion 30 and connects the latter to a second sleeve portion 36, the latter being slidably disposed upon a guide rod 38 extending transversely across the framework 16 adjacent the medial regions thereof. A coil spring 75

40 surrounds the guide rod 38 and bears at one end against the side of the framework 16 and at the other end against the sleeve portion 36, thus normally urging the casting 32 toward the left as viewed in Fig. 3 to in turn yieldably urge the sharpening wheel 12 into engagement with the bevelled edge of the slicing knife 10. A portion of the framework casting 16 is relieved to provide an opening 42 (Fig. 3) therethrough through which the sleeve portion 30 of the sharpening wheel supporting casting 32 extends along an inclined axis as viewed in Fig. 3.

The burring wheel 14 is secured by means of fastening means including a clamping screw 50 (Fig. 4) to a rotatable spindle 52 which is mounted by means of sleeve bearings 54 (see also Fig. 4) and an anti-friction thrust bearing 56 in a non-rotatable sleeve portion 58 provided on a casting designated in its entirety at 60. The casting 60 includes a web portion 62 which serves to connect the sleeve portion 58 with a second sleeve portion 64, the latter sleeve portion being slidably disposed on a guide rod 66 extending across the framework 16 at a point adjacent the outer or free end thereof. A coil spring 68 surrounds the guide rod 66 and bears at one end against one side of the framework and serves to normally urge the casting 60 to the left, as viewed in Fig. 4, to cause the burring wheel 14 to yieldingly bear against the side of the slicing knife 10 opposite the bevelled edge thereof for the purpose of removing any burrs created by the sharpening wheel 12 during the sharpening operation. The axis of the sleeve portion 58 of the casting 60 and the axis of the guide rod 66 extend substantially perpendicular to the plane of the cutting knife 10 in order that the effective sharpening surface of the burring wheel 14 may lie flush against the face of the sharpening knife 10 undergoing grinding.

The specific mounting for the sharpening wheel spindle 28 within the sleeve portion 30 of the slideable casting 32 has not been illustrated herein, but it will be understood that the same may be similar to the mounting for the spindle 52 in the sleeve 58 of the burring wheel casting 60 and consequently may include sleeve bearings and anti-friction roller bearings if desired.

Referring now to Figs. 1 and 6, the framework or casting 16 is provided with a depending web 70 on its underneath side. This web is designed for selective reception in one or the other of a pair of annular grooves 72 and 74 formed in a stationary supporting stud 76, one end of which is threadedly received as at 78 in a stationary part of the slicing machine framework, preferably the knife box casing 21. The stud 76 and shaft 20 extend in substantial parallelism and it will be seen, therefore, that by manually raising the entire knife sharpening assembly, including the guard or cover 22, the entire assembly may be slid longitudinally on the shaft 20, so that the depending web 70 may be locked in either of the grooves 72 or 74. With the web 70 locked in the groove 74 the two grinding wheels, namely the sharpening wheel 12 and the burring wheel 14, will assume a position on one side (i. e., behind) the plane of the rotary slicing knife. When the web 70 is placed within the groove 72, the two grinding knives 12 and 14 will straddle the peripheral edge of the slicing knife as shown in Fig. 3, with these grinding wheels assuming their normal dotted line position preparatory to being manually urged toward their operative sharpening positions, as shown in full lines by mechanism

subsequently to be described. In so moving the assembly from its inoperative position to its sharpening position, and vice versa, it is obvious that the same will be tilted about the axis of the shaft 20 to a sufficient elevation to cause the burring wheel 14 to clear the peripheral edge of the knife blade 10. The outer sides of the grooves 72 and 74 are preferably bevelled, as indicated at 80, and the web 70 is provided with a recess 82 which is reduced as at 84 (Fig. 6) to assist in locating the assembly in either of its two positions of rest.

An adjusting screw 86 (Figs. 2 and 6) is threadedly received in a raised portion or boss 87 provided on the framework 16 and has its extreme lower end designed for engagement with the stud 76 in order that the limiting position of the entire knife sharpening assembly may be adjusted to bring the grinding wheels 12 and 14 into proper adjusted position relative to the periphery of the knife blade 10. The adjusting screw 86 is concealed within the boss 87 by means of one of the fastening screws 24 which anchors the cover plate 22 in position on the framework 16.

As previously stated, the sharpening wheel casting 32 and the burring wheel casting 60 are normally urged by the springs 40 and 68 on the respective shafts 38 and 66 on which they are mounted toward their operative grinding positions. However, means are provided for yieldingly maintaining these members in their retracted positions against the action of their respective springs so that the normal positions of these two grinding wheels are, in fact, their retracted positions. Accordingly, a pivot pin 90 is mounted for oscillation about a vertical axis in an upstanding boss 92 provided in the base of the framework 16 and is normally urged in a counterclockwise direction, as indicated by the arrows in Figs. 2 and 5, by means of a torsion spring 94, one end of which is anchored as at 96 in the framework 16 and the other end of which is anchored as at 98 in a collar 100. The collar 100 is keyed to the pivot pin 90 and is held thereon by means of a fastening screw 102 and washer 104. The spring 94 being normally under tension, the pivot pin 90 is normally urged in a counterclockwise direction. The pivot pin 90 projects below the level of the bottom of the framework 16 and has secured thereto in any suitable manner, as for example by welding as shown at 93, an operating lever 106 having a handle portion 108 and lever portions 110 and 112, which extend in opposite directions, respectively, radially from the axis of the pivot pin 90.

The radially extending portion 112 of the operating lever 106 is designed for engagement with a lug 114 provided on the sharpening wheel casting 32 while the radially extending portion 110 is designed for engagement with a lug 116 provided on the burring casting 64 as clearly shown in Fig. 5. In this view the spring 40 is schematically shown and the accompanying arrow represents the application of force to the casting 32 in a direction tending to move the same to a position wherein the sharpening wheel 12 engages the bevelled surface of the knife 10. Similarly the spring 68 and accompanying arrow schematically represent the application of force to the casting 60 in a direction tending to move the same to a position wherein the burring wheel 14 engages the knife 10. The rate of the spring 94 however is greater than the combined rates of the two springs 40 and 68 and the leverages involved are such that the torque applied to the

5 pivot pin 90 is sufficient to normally maintain the castings 32 and 60 in their retracted positions with the springs 40 and 68 compressed so that the grinding wheels 12 and 14 remain in their retracted dotted line positions as shown in Fig. 3. Thus, with the knife sharpening assembly as a whole in its operative position with the web 70 in register in the groove 72, the grinding wheels 12 and 14 are out of contact with the knife 10.

The handle portion 108 of the actuating lever 106 extends laterally from the operative lever portion 110 and the extreme end thereof extends beyond the confines of the guard or cover 22 where it is conveniently accessible to the hand of the operator. When the handle portion 108 is released it assumes the dotted line position designated at *a* in Figs. 2 and 5 with the spring 94 serving to maintain the lever portions 110 and 112 against the respective lugs or abutments 116 and 114 respectively so as to maintain the castings 60 and 32 retracted with the grinding wheels 14 and 12 out of contact with the knife.

When the handle portion 108 is moved from its retracted position to its intermediate full line position designated at *b* in Figs. 2 and 5 due to manipulation thereof by the operator, the lever portions 110 and 112 of the lever 106 recede in a clockwise direction as seen in these views and the castings 60 and 32, and consequently the grinding wheels 14 and 12, advance under the influence of the respective springs 68 and 40 so that the wheels move into operative grinding contact with the surfaces of the slicing knife 10. Further movement of the handle toward the dotted line final position designated at *c* leaves the burring wheel 14 in grinding contact with the knife under the influence of the spring 68 and also leaves the grinding wheel 12 in contact with the knife under the influence of the spring 40. However, by means which will now be described in detail, this further movement of the lever 106 towards its final *c* position serves to apply a clamping action to the casting 32 to bind the same in fixed position so that the action of the spring 40 may ultimately be expended as the grinding operation on the bevelled surface of the knife continues until such time as the spring 40 no longer is effective to force the grinding wheel 12 against the bevelled surface of the knife.

Accordingly, almost immediately after the handle 108 of the lever 106 is moved from its *b* position toward its final *c* position, a shoulder 120 provided on the lever 106 is brought into binding contact with an edge of the lug 114 on the casting 32 and the latter is firmly and frictionally clamped between the shoulder 120 and the guide rod 38 on which the casting is slidably mounted. The operator may maintain the handle portion 108 in its *c* position for a few moments until the action of the spring 40 has been expended in the grinding operation, as determined by an aural indication evidenced by a lessening of the frictional noise attendant upon the grinding operation, after which the handle portion 108 may be released to permit the grinding wheels to assume their normal inoperative positions under the influence of the spring 94 and against the yielding action of the springs 68 and 40.

When the grinding operation has been completed, the entire sharpening assembly including the guard or cover 22 may be elevated by tilting the same on the axis of the shaft 20 and the casting 16 slid to its inoperative position with the web 70 resting in the groove 74.

Referring now to Figs. 2 and 7, it is to be noted

that the guide rod 38 on which the sharpening wheel casting 32 is slidably mounted has one end thereof loosely disposed within an opening 122 in one wall of the casting 16 and an adjusting screw 124 extends through the casting and communicates with the opening 122 at one side thereof and bears against the side of the guide rod 38 for the purpose of effecting an adjustment of the position of the end of the rod within the opening 122 to vary within small limits the axial inclination of the rod. A clamping screw 126 likewise extends through the casting and into the opening 122 for clamping the end of the guide rod 38 in any desired adjusted position. In this manner the sharpening wheel 12 may be properly oriented with respect to the cutting edge of the knife 10 during initial installation of the sharpener or readjusted after a period of use. The guide rod 56 for the casting 60 of the burr removing wheel 14 may be provided with a similar adjusting means 128 as illustrated in Fig. 2.

Changes may be made in the form, construction and arrangement of parts from those disclosed herein without in any way departing from the spirit of the invention or sacrificing any of the attendant advantages thereof, provided, however, that such changes fall within the scope of the claims appended hereto.

The invention is hereby claimed as follows:

1. In a sharpening mechanism for slicing machines of the rotary knife type, a frame, a movable grinding wheel support on said frame, a grinding wheel mounted on said support and movable bodily therewith, said support being movable in one direction from a retracted position wherein the grinding wheel is out of engagement with the knife to an advanced position wherein the wheel engages the knife for grinding purposes, spring means on said frame normally urging said support toward its advanced position, a lever mounted on said frame for oscillation about a fixed axis and having an end thereof in engagement with said support, said lever being movable from a retracted position wherein said end engages said support and holds the same in its retracted position against the action of said spring means, through an intermediate position wherein said support is moved under the influence of said spring means to its advanced position, to a final position, and a shoulder on said lever intermediate said fixed axis and end for engaging said support during movement of the lever from its intermediate position to its final position and locking the support against further movement in said direction.

2. In a sharpening mechanism for slicing machines of the rotary knife type, a frame, a movable grinding wheel support on said frame, a grinding wheel mounted on said support and movable bodily therewith, said support being movable in one direction from a retracted position wherein the grinding wheel is out of engagement with the knife to an advanced position wherein the wheel engages the knife for grinding purposes, spring means on said frame normally urging said support toward its advanced position, a lever mounted on said frame for oscillation about a fixed axis and having an end thereof in engagement with said support, said lever being movable from a retracted position wherein said end engages said support and holds the same in its retracted position against the action of said spring means, through an intermediate position wherein said support is moved under the influence of said spring means to its advanced posi-

tion, to a final position, a shoulder on said lever intermediate said fixed axis and end for engaging said support during movement of the lever from its intermediate position to its final position and locking the support against further movement in said direction, and yielding means normally maintaining said lever in its retracted position against the action of said spring means.

3. In a sharpening mechanism for rotary slicing machine knives, a frame, a movable sharpening grinding wheel support on said frame, a sharpening grinding wheel mounted on said support and movable bodily therewith, a movable burring grinding wheel support on said frame, a burring grinding wheel mounted on said latter support and movable bodily therewith, said supports each being movable in one direction from a retracted position wherein the grinding wheel thereon is out of engagement with the knife to an advanced position wherein the wheel engages the knife for grinding purposes, spring means on said frame normally urging said supports toward their advanced positions, a lever mounted on said frame for oscillation about a fixed vertical axis and engaging said supports on opposite sides of the axis, said lever being movable from a retracted position wherein it engages said supports and holds the same in their retracted positions against the action of said spring means, through an intermediate position wherein said supports are moved under the influence of said spring means to their advanced positions, to a final position, and a shoulder formed as an integral part of said lever for engaging said sharpening wheel support during movement of the lever from its intermediate position to its final position and locking the latter against further movement.

4. In a sharpening mechanism for rotary slicing machine knives, a frame, a movable sharpening grinding wheel support on said frame, a sharpening grinding wheel mounted on said support and movable bodily therewith, a movable burring grinding wheel support on said frame, a burring grinding wheel mounted on said latter support and movable bodily therewith, said supports each being movable in one direction from a retracted position wherein the grinding wheel thereon is out of engagement with the knife to an advanced position wherein the wheel engages the knife for grinding purposes, spring means on said frame normally urging said supports toward their advanced positions, a lever mounted on said frame for oscillation about a fixed axis and engaging said supports on opposite sides of the axis, said lever being movable from a retracted position wherein it engages said supports and holds the same in their retracted positions against the action of said spring means, through an intermediate position wherein said supports are moved under the influence of said spring means to their advanced positions, to a final position, and a shoulder on said lever intermediate said fixed axis and its region of engagement with one of said supports for engaging the latter support during movement of the lever from its intermediate position to its final position and locking the latter support against further movement.

5. In a sharpening mechanism for rotary slicing machine knives, a frame, a movable sharpening grinding wheel support on said frame, a sharpening grinding wheel mounted on said support and movable bodily therewith, a movable burring grinding wheel support on said frame, a burring grinding wheel mounted on said latter support and movable bodily therewith, said sup-

ports each being movable in one direction from a retracted position wherein the grinding wheel thereon is out of engagement with the knife to an advanced position wherein the wheel engages the knife for grinding purposes, spring means on said frame normally urging said supports toward their advanced positions, a lever mounted on said frame for oscillation about a fixed vertical axis and engaging said supports on opposite sides of the axis, said lever being movable from a retracted position wherein it engages said supports and holds the same in their retracted positions against the action of said spring means, through an intermediate position wherein said supports are moved under the influence of said spring means to their advanced positions, to a final position, means on said lever for engaging said sharpening wheel support during movement of the lever from its intermediate position to its final position and locking said sharpening wheel support against further movement, and yielding means normally maintaining said lever in its retracted position against the action of said spring means.

6. In a sharpening mechanism for slicing machines of the rotary knife type, a framework having a pair of parallel side portions, a cylindrical guide rod having one end thereof secured to one of said side portions, there being an opening in the other side portion into which the other end 30

of the guide rod extends, said opening being slightly larger in diameter than the diameter of said latter end of the guide rod, an adjusting screw threadedly received in said latter side portion and having an end projecting into said opening in the direction of a secant line through the opening and designed for engagement with the projecting end of the guide rod, and a clamping screw also threadedly received in said latter side portion and having an end projecting into said opening substantially diametrically thereof for clamping the projecting end of the guide rod in any desired position of adjustment, and a grinding element slidably supported on said guide rod for movement toward and away from the slicing machine knife.
